(57) **CLAIM**

The ornamental design for a keyboard with elevated keys, as shown and described.

DESCRIPTION

FIG. 1 is a first perspective view of a keyboard with elevated keys showing our new design;

FIG. 2 is a second perspective view thereof;

FIG. 3 is a top plan view thereof;

FIG. 4 is a bottom plan view thereof with keyboard legs folded in;

FIG. 5 is a front elevational view thereof;

FIG. 6 is a rear elevational view thereof;

FIG. 7 is a left side elevational view thereof;

FIG. 8 is a right side elevational view thereof;

FIG. 9 is a perspective view of a second embodiment thereof;

FIG. 10 is a top plan view thereof;

FIG. 11 is an enlarged fragmented section of keys shown on the left side of the keyboard as indicated in FIG. 1; and,

FIG. 12 is an enlarged fragmented section of keys shown on the right side of the keyboard as indicated in FIG. 1.
Broken lines shown in the drawings illustrate portions of the keyboard and form no part of the claimed design.
